[57] CLAIM

The ornamental design for a floatation collar, as shown and described.

DESCRIPTION

FIG. 1 is a top plan view of a floatation collar showing my new design;

FIG. 2 is a bottom plan view thereof;

FIG. 3 is a front elevational view thereof;

FIG. 4 is a rear elevational view thereof;

FIG. 5 is a perspective view illustrating attachment of the collar to an end of wrapped on a fishing pole;

FIG. 6 is a side view thereof on a fishing net handle; and,

FIG. 7 is another side view thereof on a gaffe handle.
The broken lines shown in FIGS. 5, 6, and 7 are for illustrative purposes only and form no part of the claim design.
